UNITED STATES PATENT OFFICE.

ALBERT J. BARTLETT, OF SHELBYVILLE, KENTUCKY, ASSIGNOR OF ONE-HALF TO GUS T. O'LEARY, OF SHELBYVILLE, KENTUCKY.

FROST-CALK FOR HORSESHOES.

No. 895,533.

Specification of Letters Patent.

Patented Aug. 11, 1908.

Application filed February 5, 1906. Serial No. 299,454.

To all whom it may concern:

Be it known that I, ALBERT J. BARTLETT, a citizen of the United States, residing at Shelbyville, in the county of Shelby and State of Kentucky, have invented a new and useful Frost-Calk for Horseshoes, of which the following is a specification.

This invention relates to means for roughing horses for slippery roads, and the objects 10 of my improvement are, to provide a frost-calk that may be quickly and easily applied, and quickly and easily removed and renewed, security against breakage or accidental loss, durability, and effectiveness. 15 These objects I attain by means of the device illustrated in the accompanying drawings, in which—

Figure 1 is a plan view; Fig. 2, a vertical transverse section on the line A—B of Fig. 1; 20 Fig. 3, a vertical transverse section on the line C—D of Fig. 1; Fig. 4, a plan view of the reverse side of the calk; and, Fig. 5, an edge view.

Similar reference numerals refer to similar 25 parts throughout the several views of the drawing.

The frost-calk 1 is adapted to fit on an ordinary horseshoe, 2, so that a special shoe need not be provided, and is intended to fit 30 on any size shoe. The calk consists of a plate having a plane face to fit against the tread of the horseshoe and provided on its plane face with a projection or flange, 9, so disposed on its face that it fits into the nail groove of the shoe, as shown in Fig. 2. On its outer edge the plate is provided with a curved flange, 6, of suitable form to embrace the outer edge of the shoe. On the outer surface or the surface opposite that which 35 works against the tread of the shoe, the calk-plate is provided with points, 3, preferably of conical form and disposed over the nail-groove and the flange 9. The flange 9 is cut out or provided with notches at two places 40 to provide spaces through which nails, 8, may pass, the notches registering with nail holes 4 and 5 through the calk-plate. The nail hole 5 is disposed between the calk-points 3 and is of a size suitable to receive an 45 ordinary horseshoe nail, having its sides tapered correspondingly with the head of the nail. The hole 4 also has its sides tapered to correspond with the head of the nail and is elongated in order to adapt the calk-plate to

fit shoes of different sizes in which the nail 55 holes are variously spaced. The plate 1 is curved as to its inner edge and tapered or feathered as shown at 7. The calk-plate may be drop forged or cast of steel that may be hardened. The calk-points 3 are hardened so as to withstand the wear against the roads, but the rest of the plate is left malleable so that portion 7 may be hammered down and bent over to embrace the inner edge of the shoe, as shown in Fig. 3. 60

The application and use of the device will now be obvious. The horse may be shod with plain shoes without toe calks. When the roads become covered with ice, the two front nails on each side may be removed by 70 filing off the clench and withdrawing the nails, the frost-calk may be applied, care being taken to remove the dirt from the nail-groove, so that flange 9 fits therein. When the frost-calk is in position on the shoe, nails of suitably larger size may be driven into the old holes, clenched as usual, and portion 7 hammered down against the inner edge of the shoe. This requires but a few moments and the horse is roughed ready for work. When 80 the points 3 become dull, the old frost-calks may be removed and discarded and new ones applied in the manner previously described. When they are no longer needed, as in continued fair weather, they may be removed 85 and the shoe fastened with suitable nails in the usual manner. The flanges 6 and 9 take the thrust due to ramming the foot against the hard street and prevent the shearing of the nails and consequent loosening and losing 90 of the calk. If the calk should become loose and begin to snap or rattle on the shoe, the nails may be drawn up, the clench hammered down and the difficulty thus overcome. The points 3 being well out towards 95 the edge of the shoe and towards the front provides a secure and firm footing.

A single nail hole, 5, may be provided and the hole 4 with the portion of the plate occupied by it may be omitted without departing 100 from the spirit of my invention.

Having thus described my invention so that any one skilled in the art pertaining thereto may make and use it, I claim—

1. A frost-calk for horseshoes, comprising 105 a plate, said plate being provided with an external up-turned flange to embrace the outer edge of the shoe, and an inner flange on the

face of said plate that works against the tread of the shoe to enter the nail-groove of the shoe, substantially as specified.

2. A frost-calk for horseshoes, comprising a plate, calk-points integral with said plate, an external up-turned flange integral with said plate to embrace the outer edge of the shoe and an inner flange to work in the nail-

groove of the shoe, said plate being provided with nail holes in the line on which said calk-points and said inner flange are arranged, substantially as specified. 10

ALBERT J. BARTLETT.
